SERVO POWER APPLICATION TO DIES OF DIE-CASTING MACHINES

Louis H. Morin, Bronx, N. Y., assignor of one-half to Davis Marinsky, Bronx, N. Y.

Application August 14, 1942, Serial No. 454,810

16 Claims. (Cl. 22—68)

This invention relates to die casting machines and to the operation of dies of machines of this type and kind. More particularly, the invention comprises the application of "servo-power" to the dies, preparatory to the pressure injection of casting material into the dies to insure firm engagement of the dies and to resist the pressure of the casting material injected into the die; and still more particularly to the hydraulic closing of dies of high speed die casting machines. The novel features of the invention will be best understood from the following description when taken together with the accompanying drawing, in which certain embodiments of the invention are disclosed, and in which the separate parts are designated by suitable reference characters in each of the views; and in which:

Fig. 1 is a diagrammatic sectional view through the dies of a casting machine showing the same in closed position.

Fig. 2 is a view similar to Fig. 1 showing the dies in open position; and

Fig. 3 is a view similar to Fig. 1 showing the dies improperly closed.

In the die casting art, it has been known to provide machines employing hydraulic or pneumatic pressures for closing the dies. However, this has been accomplished by what may be termed a direct stroke which involves rather complicated mechanism and a material waste of power, in that the entire operation of the dies has been through the medium employed. Furthermore such methods of operation are not practically applicable to what might be termed high speed die casting machines.

It is the purpose of my invention to provide a "servo-power" application to the dies, momentarily at the point of the cycle when the dies are to be held firmly closed, that is to say, when the casting material is pressure injected into these dies. In other words, this application of power or pressure in closing the dies is employed in conjunction with and as part of the other mechanical means for moving the dies toward and from each other. Furthermore, safety means are employed to prevent injury or destruction to the dies and other working parts of the machine, and also to eliminate accidents which might occur by pressure injection of casting material into improperly closed dies, by the squirting of this material beyond the limits of the dies or the die cavity. Further, by reason of the momentary application of the "servo-power" extremely economical and relatively fool-proof operation of

the machine is provided, particularly from the standpoint of die operation.

From the standpoint of mechanical operation of the dies, herein diagrammatically illustrated and described in brief, reference can be made to the more specific disclosure of the entire operating structure in U. S. patents, 1,975,966 dated October 9, 1934, and 2,193,832 dated March 19, 1940, in which patents are illustrated types of casting machines to which the present invention is applicable.

It will be understood, however, that the disclosure of the invention in this respect is only illustrative of one adaptation and use of my invention.

In the accompanying diagrammatic illustration, the mechanism controlling die operation is applied to only one of the dies, the other die being shown only in part, but it will be apparent that the same structure will be used in conjunction with both dies, particularly in casting machines where both dies are movable relatively to each other and away from a core which supports the finished casting and which is used to eject the casting from the impression or cavity of both die parts.

In the drawing, 10 represents each die part. These die parts are moved toward and from each other by die operating slide rods 11 having angular key elements 12 fitting in corresponding grooves 13 in the die parts so that, as the rods 11 move back and forth at right angles to the longitudinal plane of the die parts 10, the dies are opened and closed as is specifically taught in the patents hereinbefore cited.

With the present structure, the die parts 10 are each provided with long bores or passages 14, which form cylinders, into which a hydraulic or other pressure medium may be injected through pipes or tubes 15 communicating with admission ports 16 which open into the cylinders 14 adjacent the ends of the die parts having the cavities 17.

In the cylinders 14 are arranged pistons or plungers 18, which extend through the outer ends of the die parts and have enlarged heads 19 provided on outer surfaces with projecting control fingers or dogs 20 which form extensions on the piston, which operate in conjunction with pawls 21.

Supported on the outer end of the dies are pins 22 which pass through openings in the enlargement 19 of the pistons, and springs 23 are mounted on the pins outwardly of the enlargement and tension of these springs is controlled

by adjustment nuts 24 arranged on the pins 22. The springs 23 maintain the pistons 18 in normal inwardly projected arrangement in the cylinders 14, which inward movement is checked by stops 25.

The pawls 21 are rotatably supported on shafts 26, the pawls comprising a finger 27, notched as seen at 28, to engage the outer end of the dog 20, as seen in Fig. 1 of the drawing. The pawls 21 also include a finger 29 adapted to operatively engage a micro-switch 30 or the sensitive plunger 31 of said switch for purposes later described. At 32 is shown a rod pivoted to the pawl 21 for actuating said pawl in the cycle of operation of the machine to bring the pawl into the position shown in Fig. 1 slightly in advance of the application of the "servo-power" and also to raise the finger 27 to allow normal opening of the dies after the casting has been formed, as is indicated in Fig. 2.

The cycle of operation of the machine will be readily understood from the foregoing description when taken in connection with the diagrammatic illustrations in the drawing and the following statement. Considering Fig. 1, it will be assumed that the dies 18 have been moved into closed position and the pawl 21 brought into the position to engage the dog 20 in the recess 28 of the finger 27 of the pawl. At this time and through suitably controlled means oil or other pressure element is introduced into the cylinders 14 through the tubes or pipes 15, thus applying the "servo-power" to the dies 18 to firmly support the same in closed position. In the same instant or very shortly thereafter in the cycle of machine operation, casting material is pressure injected into the dies at the parting line 33 thereof through a gate or admission passage, not shown, in that it is disposed at right angles to the dies, to form a casting 34 in the cavities 17 and around a core pin 35. Immediately thereafter the hydraulic or other pressure is released from the cylinders 14 and the dies are moved into open position as illustrated in Fig. 2, the pawl 21 having been raised through operation of the rod 32, as will be apparent. After removing the casting, the dies are again closed and the above cycle of operation is repeated.

As heretofore pointed out, my improved application of "servo-power" to the dies is particularly adaptable for use in what is termed a high speed die casting machine, wherein the dies are opened and closed one hundred or more times a minute and operations of this type and kind have been performed at speeds of eight to nine hundred per minute. It will thus be apparent that the moment of application of the "servo-power" in each cycle of machine operation represents in fact a small fractional part of each complete cycle of machine operation and a fraction of a second.

In Fig. 3 of the drawing is diagrammatically illustrated the fool-proof operation of the machine, for example, in the event that the dies 18 become improperly closed by the presence of some foreign particle, as indicated at 36 in Fig. 3 between adjacent surfaces of the dies 18. In such instances the dog 20 will check downward movement of the pawl 21 or the finger 27 thereof so that this finger will rest upon the upper surface 37 of the dog, thus maintaining the finger 29 out of operative engagement with the plunger 31 of the switch 30. The machine will perform its normal operation. In other words, the hydraulic or other pressure medium will be intro-

duced into the cylinder 14, but since the piston is unsupported by the pawl finger 27, this pressure will operate to move the piston 18 outwardly, as indicated partially in dotted lines in Fig. 3 against the action of the spring 23, the dog 20 sliding under the finger 27 in this operation. The switch 30 controls the application of hydraulic pressure to the casting material and in order for the casting material to be injected into the dies, the switch plunger 31 must be depressed slightly. Failure to operate this switch renders the pressure injection of the casting material inoperative, thus accidental discharge or squirting of the casting material through the partially closed dies is obviated. The machine will continue to operate without the production of castings until the foreign particle or obstruction is removed and if one operator is attending many automatic machines of this type and kind, suitable signal devices can be employed to indicate faulty operation of the machine, which devices are old and known in the art. In addition to eliminating pressure injection of the casting material in improperly closed dies, it will also appear that the application of the "servo-power" is relieved through the free action of the piston; thus injury or destruction to the dies is obviated.

It will be apparent that the pawl 21 operates in the manner of a latch, which may be said to engage a bolt 20, the dog extension on the piston, in checking outward movement of the piston and will be constructed in such manner as to provide the required backing up of the piston to care for the application of the "servo-power" in closing and holding the dies closed for the moment of pressure injection of the casting material.

In the diagrammatic illustrations, all structural details with respect to packings of the pistons, etc. have been omitted as these are all well known in the arts. Furthermore, the invention is applicable to die casting machines of various types and kinds and in fact to any type and kind of mechanisms where it is desirable to apply a final pressure or stroke upon a moving part which has been otherwise moved into a predetermined position. In accordance with the present teachings, the medium employed is introduced between the moving part and what might be termed a backing member, automatically actuated means being employed controlling operative position of the backing member and otherwise controlling operation of the machine or apparatus.

Having fully described my invention, what I claim as new and desire to secure by Letters Patent is:

1. In die casting machines, a pair of dies movable toward and from each other, mechanical means for actuating said dies, a member forming a backing for each die and movable relatively to the die, means for injecting a pressure medium between the die and said backing member to sustain the die in closed position, and a stop for said member adapted to be positioned in an operative or inoperative position.
2. In die casting machines, a pair of dies movable toward and from each other, mechanical means for actuating said dies, a member forming a backing for each die and movable relatively to the die, means for injecting a pressure medium between the die and said backing member to move the die into closed position, means controlling the operative backing up position of said member, said last named means comprising a bolt on said member, and a latch engaging the bolt to support said member in operative position.

3. In die casting machines, a pair of dies movable toward and from each other, mechanical means for actuating said dies, a member forming a backing for each die and movable relatively to the die, means for injecting a pressure medium between the die and said backing member to move the die into closed position, means controlling the operative backing up position of said member, said last named means comprising a bolt on said member, a latch engaging the bolt to support said member in operative position, and means preventing operative engagement of the latch with said bolt in improper, mechanical, closing movement of the die.

4. In die casting machines, a pair of dies movable toward and from each other, mechanical means for actuating said dies, a member forming a backing for each die and movable relatively to the die, means for injecting a pressure medium between the die and said backing member to move the die into closed position, means controlling the operative backing up position of said member, said last named means comprising a bolt on said member, a latch engaging the bolt to support said member in operative position, means preventing operative engagement of the latch with said bolt in improper, mechanical, closing movement of the die, and said last named means including means preventing injection of casting material into improperly closed dies.

5. In a die casting machine, a pair of dies movable toward and from each other, said dies having cylinder portions, pistons operating in the die cylinders, means comprising a latch adapted to operatively engage the piston of each die cylinder, means for controlling normal mechanical movement of the dies toward and from each other, and means for introducing a pressure medium between the dies and said pistons to sustain the dies in closed position, while said pistons are backed by said latch controlled means.

6. In a die casting machine, a pair of dies movable toward and from each other, said dies having cylinder portions, pistons operating in the die cylinders, means comprising a latch adapted to operatively engage the piston of each die cylinder, means for controlling normal mechanical movement of the dies toward and from each other, means for introducing a pressure medium between the dies and said pistons to sustain the dies in closed position, while said pistons are backed by said latch controlled means, and means providing yieldable movement of the pistons relatively to said dies.

7. In a die casting machine, a die, mechanical means for moving the die into open and closed positions, said die having an elongated cylinder, a piston in said cylinder and projecting outwardly through one end of the die, means in the die for introducing a pressure medium into the cylinder at the other end of said piston to move the die into closed position, means operatively engaging the first named end of the piston to form a backing maintaining the piston against movement in the aforesaid closing movement of said die, and means releasing said last named means in moving the die into open position.

8. In a die casting machine, a die, mechanical means for moving the die into open and closed positions, said die having an elongated cylinder, a piston in said cylinder and projecting outwardly through one end of the die, means in the die for introducing a pressure medium into the cylinder at the other end of said piston to move the die into closed position, means operatively engaging the first named end of the piston to

form a backing maintaining the piston against movement in the aforesaid closing movement of said die, means releasing said last named means in moving the die into open position, and said backing means comprising a latch engaging a projecting bolt on said piston.

9. In a die casting machine, a die, mechanical means for moving the die into open and closed positions, said die having an elongated cylinder, a piston in said cylinder and projecting outwardly through one end of the die, means in the die for introducing a pressure medium into the cylinder at the other end of said piston to move the die into closed position, means operatively engaging the first named end of the piston to form a backing maintaining the piston against movement in the aforesaid closing movement of said die, means releasing said last named means in moving the die into open position, said backing means comprising a latch engaging a projecting bolt on said piston, and spring means supporting the piston in predetermined position in the cylinder of the die and providing relative movement between the die and piston.

10. In a die casting machine employing mechanically actuated dies movable toward and from each other, in moving the dies into closed and open positions, means for applying servo-power to the dies in closing and holding the dies closed during pressure injection of casting material into the dies, and means automatically relieving the servo-power application in the event of improper mechanical closure of said dies.

11. In a die casting machine employing mechanically actuated dies movable toward and from each other, in moving the dies into closed and open positions, means for applying servo-power to the dies in closing and holding the dies closed during pressure injection of casting material into the dies, means automatically relieving the servo-power application in the event of improper mechanical closure of said dies, and said last named means including means stopping pressure injection of casting material into improperly closed dies.

12. The combination with dies of a die casting machine, of a backing member for the die, means cooperating with said member retaining the same in fixed backing-up position, means yieldably coupling the die with said member, and means for introducing a pressure medium between the backing member and the die in applying servo-power to the die in supporting the die in closed position.

13. In an apparatus of the class described, an element movable into open and closed positions, means for moving said element, said element having a cylinder, a piston in said cylinder, yieldable means coupling the piston and element providing movement therebetween, while normally maintaining predetermined position of the piston in the cylinder of said element, a catch device automatically movable into and out of engagement with said piston to form a backing for said piston maintaining a predetermined position thereof, and means for introducing a pressure medium into the cylinder of said element to move the element relatively to the piston, while the piston is maintained in backed position.

14. The combination with a die of a die casting machine having means mechanically moving the die into open and closed position, of a backing member movable with the die in normal opening and closing movement thereof, means automatically engaging said member to support the same

in backing-up position, and means injecting a pressure medium between the backed up member and the die to urge the die in a direction away from said member in moving the die into closed position.

15. In a die casting machine employing dies movable toward and from each other, mechanical means for actuating said dies, each die having a cylinder and a backing member therein, and means for introducing a pressure medium into 10 said cylinders between said backing members and dies for applying holding pressure directly to the dies at the moment of forming a casting within said dies.

16. In a die casting machine employing dies movable toward and from each other, mechanical means for actuating said dies, each die having a cylinder and a backing member therein, means for introducing a pressure medium into said cylinders between said backing members and dies for applying holding pressure directly to the dies at the moment of forming a casting within said dies, and means controlling the last named operation of said dies.

LOUIS H. MORIN.
